Specification of Letters Patent.

Patented May 28, 1918.

Application filed March 31, 1917. Serial No. 158,841.

To all whom it may concern:

Be it known that I, WILLIAM J. WRIGHT, a citizen of the United States, residing at Oakland, in the county of Alameda and State of California, have invented new and useful Improvements in Wrenches, of which the following is a specification.

This invention relates to wrenches, and has for its object to simplify and improve the construction and operation of such devices.

The particular type of wrench to which this invention relates is best represented by my Patent #596,476 dated September 25, 1894. In the prior wrench the handle is connected to and slideable with the inner jaw, the outer jaw being fixed to the shank and the adjustment accomplished by a pawl carried on the handle and coöperating with a series of yielding, separable plates on the shank, forming teeth, to retain the pawl in any position of adjustment. The yielding, separable plates are made thin and tapered at their outer ends, and afford an ideal arrangement for securing the minutest adjustment of the jaw, since the pawl will find an entrance between these plates in any position it may occupy. This is not possible with fixed teeth.

However, several difficulties are present in the prior wrench which renders it unsuitable for practical and commercial uses. In the first place it requires two hands to adjust the jaws. This is so because the handle is slideable on and incloses the shank, and one hand must be used to hold the handle and the other to engage the outer jaw and move it relatively. In my present invention I overcome this objection by fixing the handle upon the shank and sliding the inner jaw relatively with the handle, whereby the thumb of the same hand may be used to slide the inner jaw back and forth upon the shank. Another objection in said prior wrench is that the pawl must be moved in both directions by hand and is held in locked position between the teeth by a special form of latch difficult to manipulate and uncertain in operation. In the present device I have given the pawl an automatic action, it being automatically forced into locked position when moved in a direction to engage the teeth and positively held in engagement by a spring pressed latch. A spring returns the pawl to disengaged position when the latch is released. The pawl is

therefore always certain to engage with the teeth and be locked in such position when depressed, inasmuch as the spring pressed latch serves to force the pawl into a locked position and positively retains it in engagement with the teeth. If the pawl is not depressed sufficiently far to engage the teeth, the latch will not come into play and therefore the pawl will be instantly returned by its spring. In the prior wrench there was nothing to compel engagement of the pawl with the teeth and therefore in many instances the pawl was liable to stop short of engagement and allow the jaws to remain unlocked without the knowledge of the operator. In short, I have produced in a wrench of this type a one handed adjustment wherein an easily operable, quick and positive control for the adjusting mechanism is provided.

One form which my invention may assume is exemplified in the following description and illustrated in the accompanying drawing, in which Figure 1 shows a perspective view of a complete wrench embodying my invention.

Fig. 2 shows a longitudinal sectional view of the same.

Fig. 3 shows an edge view of the shank portion of the wrench and the yielding, separable plates in position thereon.

Fig. 4 shows a sectional view taken on the line 4—4 of Fig. 2.

Fig. 5 shows a sectional view taken on the line 5—5 of Fig. 2.

In general the wrench comprises a shank 10 which forms the handle, a jaw 11 on the outer end of the shank, and a jaw 12 and sleeve 13 slideable on the shank. In a recess 14 on the shank is a pile of thin plates 15, independent and separable and yieldably pressed together by a spring 16 or other cushioning device. The plates are tapered at their exposed ends to form finely divided teeth movable sufficiently to conform to any position the pawl 17 may occupy. This pawl is movable up and down in a shoulder 18 formed on the sleeve, and has a wedge shaped extension 19 to coöperate with the teeth or plates. A spring 20 presses the pawl upwardly and normally retains it in position disengaged from the teeth.

On the front side of the pawl is a rounded lug 21 with which coöperates a latch device 22 the latter pivoted at 23 upon a forward extension of the sleeve 13. The said latch

is provided with a head portion 24 having an inwardly extending projection or shoulder 25, for coöperation with the lug 21. The said shoulder is preferably square on its lower side, and rounded on its upper side, so that when the pawl is depressed the shoulder will engage the upper side of the lug and retain it in depressed position.

A V shaped spring 26 presses the latch device inwardly and retains it yieldingly in position where the shoulder 25 will coöperate with the lug 21. A flange 27 on one side of the latch permits the operator by inward pressure thereon, to move the latch in a direction to disengage the shoulder 25 from the lug. The rounded upper portion on the lug on the shoulder will allow the lug 21 to slip by in moving downwardly, and as the lug passes the point of the shoulder, the latch will be moved inwardly by its spring 26 to position where the shoulder will overlie the lug and retain the pawl in the locked position. Moreover the rounded shape of the lug 21, will permit the pointed shoulder 25 to assist in forcing the pawl into locked position after it has passed a certain point. A pin 28 on the shank limits the outward sliding movement of the sleeve 13 and jaw 12.

The operation of the device is simple and convenient. The operator with the palm of his hand grasps the handle portion of the shank, and has his thumb and forefinger free whereby to manipulate the sleeve and jaw in a back and forth direction to any desired position of adjustment. He presses downwardly on the pawl to lock the parts in adjusting position, and presses inwardly on the latch to release the pawl. If the pawl is not depressed sufficiently far to engage the teeth, then the latch will not come into play and the spring 20 will instantly return the pawl, so that the operator knows that the parts are not locked. This gives a certain and positive operation that is in strong contrast with my prior wrench, wherein the pawl was not spring pressed outwardly, and there was no quick way of determining whether or not the lock had been set.

The device herein shown and described may be varied and modified in many respects without departing from the spirit of my invention as disclosed in the appended claims.

Having thus described my invention, what

I claim and desire to secure by Letters Patent is—

1. A wrench comprising a shank having a fixed jaw on one end and a handle on the other, a jaw slideable on the shank and having an extension lying in close proximity to the handle, a series of teeth formed on the shank, a depressible pawl on the extension of the slideable jaw to coöperate with the teeth whereby the distance between the jaws may be varied, the outer portion of the pawl projecting through the extension for engagement by the thumb to permit the same to be depressed, a spring for lifting said pawl out of engagement with the teeth, a pivoted latch device on the extension of the slideable jaw adjacent the handle to engage a projection on the pawl for retaining the latter depressed and a spring for holding the latch in engagement with said projection, said latch having means formed upon it engageable by the thumb to retract the same for releasing the pawl.

2. A wrench comprising a shank having a fixed jaw on one end and a handle on the other, a jaw slideable on the shank and having an extension lying in close proximity to the handle, a series of teeth formed on the shank, a depressible pawl on the extension of the slideable jaw to coöperate with the teeth whereby the distance between the jaws may be varied, the outer portion of the pawl projecting through the extension for engagement by the thumb to permit the same to be depressed, a spring for lifting said pawl out of engagement with the teeth, a pivoted latch device on the extension of the slideable jaw adjacent the handle to engage a projection on the pawl for retaining the latter depressed and a spring for holding the latch in engagement with said projection, said latch having means formed upon it engageable by the thumb to retract the same for releasing the pawl.

In testimony whereof I have hereunto set my hand in the presence of two subscribing witnesses.

WILLIAM J. WRIGHT.
